5 Claims. (Cl. 51—50)

1

The present invention refers to a method of grinding, particularly of internal surfaces, bore holes and the like in work pieces having a rotary movement and a simultaneous reciprocating movement imparted thereto, the latter movement being performed in the axial direction of two coaxially mounted rotating grinding tools. In grinding machines of this kind, the work piece is generally arranged in a holder, which may be swung in a plane at right angles to the grinding spindles, in order to render possible insertion and removal and controlling measurement of the work piece. To permit this oscillatory movement of the holder, the grinding tools would hitherto be generally arranged at so great a mutual distance on both sides of said holder that the work piece or the holder thereof might be moved into and out of operative position without being prevented therefrom by the grinding tools. This arrangement of the grinding tools at a relatively great mutual distance suffers from the drawback that the grinding tools will leave the grinding surface for each stroke of the work piece during the reciprocating movement of the work piece, and will again be moved in onto the same when the direction of movement is reversed. It has been found that a bore hole ground in this way will not become exactly cylindrical, but obtains at the ends thereof a somewhat larger diameter than the remainder of the bore hole. The reason of this is the inconsiderable resiliency of the grinding spindle caused by the pressure of the grinding tool on the grinding surface, said resiliency involving a certain even if immaterial deviation of the grinding tools from the centered position taken by the same in their unloaded state. The present invention has for its object to obviate this disadvantage, and principally consists in that the grinding tools are adjusted, prior to the grinding operation, in the axial direction relatively to each other so as to be located at a mutual distance which is smaller than the length of the surface to be ground, whereupon the work piece will have imparted thereto a reciprocating movement limited in such manner that the grinding tool does not leave the grinding surface altogether during the grinding operation. For example, if a throughbore in a work piece is to be ground along the whole of its length, the grinding tools are adjusted to a mutual distance, which is approximately equal to or smaller than half the length of the bore. To facilitate such axial adjustment of the grinding tools, the grinding spindle housings, wherein the grinding spindles are mounted, are axially

2

displaceable, according to the invention, in guiding bearings of the machine frame while being provided with clutching means, by which the grinding spindle housings may be locked in every position of adjustment. It is important therefore, that the clutching means be constructed in such manner that the loosening and securing of the spindle housings does not involve any displacement of the coaxial position of the grinding spindles. To this end, each spindle housing is provided, according to the invention, with two clamping devices arranged to effect clamping of the spindle housing in its guiding bearing and to be actuated by a common tightening contrivance which is so arranged and balanced that the tightening power will be equally distributed on both clamping devices. Preferably, the two clamping devices are for this purpose adapted to be actuated by means of a leverage comprising two levers connected at the ends thereof with the clamping members of the two clamping devices, said levers being actuated at the centre thereof by the common tightening contrivance, so that the tightening power is distributed through the levers to the same extent onto the two clamping devices.

The invention will be described more closely with reference to the accompanying drawings, which illustrate a form of embodiment of a grinding machine constructed in accordance with the invention. Figure 1 is a plan view showing the most important parts of the machine. Figure 2 is an axial section through the bearing housing for a rotating chuck. Figure 3 is a cross section through the clutching means for one of the grinding spindle housings. Figure 4 shows the clutching means viewed in elevation, and Figure 5 is a plan view of the upper part of the clutching means.

40 The machine is provided with two grinding spindles 1, 2 carrying at the free ends thereof a grinding roller 3 and 4 respectively, said spindles being mounted in cylindrical grinding spindle housings 5 and 6 displaceable in guiding bearings arranged in brackets 7 and 8, respectively, which are rigidly connected with the machine frame, only a portion 9 of which is shown in Figure 1. The latter part with the brackets 7, 8 and the grinding spindle housings arranged thereon is displaceable on guides in a direction perpendicular to the grinding spindle axis. The grinding spindles, as well as the appertaining grinding spindle housings are conically arranged relatively to each other and displaceable in the axial direction by a displacement of the grinding

spindle housings in the guiding bearings or bores in the brackets 7, 8, which bearings or bores are likewise coaxial. The grinding spindles are arranged to be operated by means of turbines enclosed within hoods 11, 11 and arranged on the extreme end of the spindle housings, said turbines being driven by means of compressed air supplied through passages in the machine frame and through flexible tubes 12, 13. The axial adjustment of the grinding spindle housings is effected with the aid of handles 14, 15 in the form of double-armed levers, which are mounted in arms 16, 17 projecting from the brackets 7, 8, and which are coupled to the grinding spindle housing by means of bifurcated members not visible in the drawings, said members grasping about flanges 18, 19 on the turbine casings. For the purpose of effecting an accurate axial adjustment of the grinding spindles in the operative position, there are provided stop screws 20, 21, which are screwed through threaded holes in the flanges 18, 19, and which, when the grinding spindles are adjusted inwardly, are caused to bear with their ends on abutting surfaces on the brackets 7, 8. During the adjustment of the grinding spindles, the grinding spindle housings may move freely in the respective recesses in the brackets 7, 8. After the adjustment has been effected, the grinding spindle housings are each locked by means of a clutching device, the construction of which will appear more closely from Figures 3-5.

The grinding spindle housing 6 is displaceably mounted in a bore in the bracket 8, wherein it is fitted as accurately as possible, and is adapted to be locked in the position of adjustment by means of two similarly constructed clamping devices arranged at a suitable axial distance from each other. In the example shown, each of these clamping devices consists of a piston 23 displaceable in a bore 22 and of a sleeve 24, which is likewise displaceable in the same bore, said piston and sleeve being bevelled off at the end portions thereof bearing on the spindle housing, so as to form a uniform bearing surface in these places against the wall of the spindle housing projecting into the bore 22. The piston 23 is provided with a pulling rod 25 extending through the sleeve 24, said rod being drawn through apertures in two levers or yokes 26, 27 and being provided at the upper end thereof with nuts 28 threaded thereon, said nuts bearing against the upper side of the yoke 27. The lower yoke 26 bears on the end 29 of the sleeve 24 projecting over the bracket. The upper yoke 27 is provided at the centre thereof with a threaded bore having a clamping screw 30 screwed into the same, said clamping screw abutting with its lower end against the upper side of the lower yoke 26 and being provided with a head 31 and a handle 32 connected thereto, by means of which the clamping screw may be turned to tighten up the two clamping devices. By the turning of the screw 30 by means of the handle 32, the two yokes are pulled apart while exerting a downward pressure on the sleeves 24 and an upward pull on the rods 25, so that the two clamping members 23, 24 are set against the spindle housing so as to rigidly lock the same in its position of adjustment. Through the arrangement described of the two yokes and the tightening means 30, 31, 32, the tightening power is distributed equally on the two clamping devices, in a manner such that every oblique positioning of the grinding spindle housing in its

10
15
20
25
30

guiding bearings is prevented. Since the two clutching devices are of the same construction and arrangement relatively to the respective grinding spindle housings 5, 6, safety is ensured for non-displacement of the coaxial position of the grinding spindles. As a further measure of safety for this purpose, there are provided stop abutments in the form of pins 33 on the upper yokes 27, in such manner that the magnitude of the tightening power is limited and may be kept as far as possible equal on the two grinding spindle housings.

As will appear from Figure 2, the work piece in the example shown consists of a sleeve 34 provided with a through-bore intended to be ground on the inside thereof. The work piece is intended to be fixed in a coaxial position within a chuck 35, which is rotatably mounted in a bearing head 36 constituting a portion of a swingable holder 37 for the work piece. The bearing casing is provided with two annular bearing sleeves 38, 39 retained by rings 40, 41 screwed into the bearing head. The clutching of the work piece is effected by means of a slotted sleeve 42, which is moved in between a cylindrical portion of the work piece and a conical portion of the chuck by means of a sleeve 43 threaded into the chuck 35. The interior of the bearing housing is covered outwardly by the annular plate 40, on the one hand, and, on the other hand, by a plate 44 screwed fast into the chuck 35.

The chuck 35 is adapted to be driven from a motor, not illustrated in the drawing, through the agency of a belt 45, which is laid into a belt groove 46 in the chuck, and which is driven from a pulley 47 which, in turn, is coupled to the motor through a worm wheel 48 and a worm 49, the shaft of which is extended through a slit 50 in the wall of the hollow holder 37. The holder 37 is swingably mounted in a pin 51, on the one hand, and, on the other hand, in a pin coaxial therewith on a journal not illustrated in the drawing, said journal fitting into a through-hole 52 in the wall of the holder. The pulley 47 and the worm wheel 48 are arranged on a shaft mounted within the holder 37, said shaft being coaxial with the oscillatory axis of the holder. Thanks to the swingable arrangement of the holder 37, the bearing head with the work piece arranged therein may be swung into and out of the working position shown in Figure 1. When the work piece is to be subjected to a controlling measurement, or is to be removed, the holder 37 is swung round by 180°. At the same time, an adjusting tool in the form of a grinding diamond arranged on the holder is brought into working position to turn down the cylindrical working surfaces of the grinding rollers.

As will be seen from Figure 1, the motion transmitting means between the rotating chuck 35 and the appertaining driving motor is entirely encased within the holder 37 and the bearing head 36 connected thereto. To close the slit 50, through which the motor shaft is extended, there is provided a ring 54 on the outside of the holder in a position coaxial relatively to the turning axis of the holder, the motor shaft then extending through a hole in said ring, which consequently does not participate in the oscillatory movement of the holder 37. The holder 37 and the driving motor are arranged in common on a slide or the like not shown in the drawing, said slide having a reciprocating movement imparted thereto by means of motive power, in a direction paralleling the grinding spindles.

Before the grinding operation is commenced,

the grinding rollers 3, 4 are adjusted by means of the handles 14, 15 and the screws 20, 21 into a working position relatively to each other adapted to the work piece in consideration, whereupon the grinding spindles and the grinding disks are turned down by means of the diamond 53. After that, the grinding spindles are moved apart by means of the handles 14, 15, the holder 37 with the work piece inserted therein being turned down into its working position, in which the holder bears on an abutment on the frame of the machine. Then the grinding disks are introduced by means of the handles 14, 15 into the bores in the work piece, so as to take the previously adjusted position. The grinding rollers are then caused to bear on the insides of the bores by the frame part carrying the brackets 7, 8 being displaced in its guides at right angles to the axial direction of the grinding spindles. The grinding process is performed in known manner by a reciprocating movement being imparted to the holder 37, said movement taking place in the axial direction of the grinding spindles. According to the invention, the grinding rollers should be so adjusted relatively to each other that none of them leaves the grinding surface during the grinding operation but is always kept in contact with the latter. To this end, the grinding rollers should be so adjusted as to come on a mutual distance which, counted between the end surfaces of the rollers facing one another, or between the centre points of the rollers, is equal to or smaller than half the length of the bore hole to be ground.

I claim:

1. A grinding machine, particularly a machine for grinding internal surfaces of work pieces, comprising two coaxially mounted rotating grinding tools operating upon a single uninterrupted surface of the work piece and relatively spaced a distance apart which is smaller than the length of the surface to be ground, two grinding spindles carrying the two grinding tools and coaxially mounted in cylindrical bearing housings, and a holder for the work piece swingably arranged between the grinding spindle housings, which latter are axially displaceable in guiding bearings in the machine frame and provided with clutching means by which the grinding spindle housing may be locked in every position of adjustment, each spindle housing being provided with two clamping devices

adapted to effect clamping of the spindle housing in its guiding bearings and to be actuated by a common tightening contrivance which is so arranged that the tightening power will be equally distributed on both clamping devices.

5 2. A grinding machine according to claim 1, the two clamping devices being adapted to be actuated by means of a leverage comprising two levers connected each at the end thereof with a clamping member in the respective clamping device, said levers being adapted to be actuated at the center by means of a common tightening contrivance so that the tightening power is distributed through the levers equally on the two clamping devices.

10 15 3. A grinding machine according to claim 1, the clutching means of the two spindle housings being of the same construction and arrangement relatively to the respective grinding spindle housings in order that the spindles shall always maintain their coaxial position.

20 25 4. A grinding machine according to claim 1, the swingable holder for the work piece consisting of a closed hollow body containing the motion transmitting members through which the motion is transmitted from a driving motor to the rotating chuck or the like in which the work piece is to be secured.

25 30 35 40 5. A grinding machine according to claim 1, the swingable holder for the work piece consisting of a closed hollow body containing the motion transmitting members through which the motion is transmitted from a driving motor to the rotating chuck or the like in which the work piece is to be secured, the motion transmitting members comprising a belt running on the one hand over the chuck and on the other hand over a pulley which is preferably coaxially arranged relatively to the oscillatory axis of the holder.
